POWER TRANSMISSION

Albert M. Lane, Detroit, Mich., assignor to Vickers
Incorporated, Detroit, Mich., a corporation of
Michigan

Application March 30, 1946, Serial No. 658,483

15 Claims. (Cl. 60—52)

1

This invention relates to power transmissions, particularly to those of the type comprising two or more fluid pressure energy translating devices, one of which may function as a pump and another as a fluid motor.

This invention is particularly concerned with flow control devices and especially with those of the type comprising a compensating valve and throttle. Such controls are well known in the art, particularly as employed in transmission panels for machine tools as illustrated in Patent No. 2,267,177 to Twyman and Patent No. 2,303,946 to Miller.

Reciprocating, double-acting piston motors are generally employed in the art for operating machine tool tables. The operating fluid pressure and volume are maintained constant by the flow control device, and therefore, to equalize the rate of travel of the motor piston and work table, it has been the practice in the past to employ a through rod for the piston. In other words, the piston rod extends in both directions from the piston to the opposite ends of the cylinder, thereby providing equal displacement for each end of the motor. By employing the well-known pressure-actuated compensating valve in combination with a throttle, the flow rate and table speed were accurately controlled and equalized in both directions.

It has been found desirable to increase the fluid flow rate during certain portions of the hydraulic transmission cycle. Such a condition is inherent when the hydraulic reciprocating motor is of the differential-piston type and where the piston rod extends only from one side of the piston to the head of the cylinder.

In that case the displacement of the one side of the motor is greater than the other. It is evident that a constant flow rate through the combination throttle and compensating valve control will produce two different rates of work table travel in proportion to the motor piston displacements. If it is desirable to maintain equalized table travel in both directions, then the flow rate must vary with the displacement of the load device.

Therefore, the general object of this invention is to provide means for automatically modifying the operation of the combination throttle and compensating valve flow rate control.

Another object is to provide hydraulic means for varying the compensating valve operation only during a pre-determined portion of the operating cycle.

More specifically, an object of the invention

is to provide an increase or decrease in pressure fluid flow during a portion of the operating cycle in proportion to the displacement characteristics of a load device.

5 A further object is to provide auxiliary hydraulic means for modifying the compensating valve operation during the period of supplying a load device requiring such modified flow, said auxiliary means being provided with hydraulic operating fluid from the supply source only during that period.

The standard flow rate control, comprising a throttle in combination with a pressure-balanced, piston-actuated compensating valve, includes a 15 spring of pre-determined tension establishing the calculated flow rate. One of the objects of this invention is to provide means for varying the compression of that spring for increasing or decreasing the calculated flow rate.

In accordance with the preferred form of the invention illustrated herein, it is also an object to provide a transmission system employing a differential-piston type of hydraulic motor for operating a machine tool work table at equal 20 rates of travel in each direction.

A further object is to provide a compact control panel for housing the transmission controls.

Further objects and advantages of the present invention will be apparent from the following 30 description, reference being had to the accompanying drawing wherein a preferred form of the present invention is clearly shown.

In the drawing:

The single figure illustrates a diagrammatic 35 view of a grinder table and control panel incorporating a preferred form of the present invention.

Referring now to the drawing, a pump 10 driven by a prime mover 12 has a suction conduit 14 through which fluid may be drawn from a tank 16 to an operating pressure conduit 18. The conduit 18 extends to a chamber 20 of a compensating valve 22 which is in a control panel 24 and is adapted to bypass fluid to tank 16 by a relief conduit 26 and a tank conduit 28 whenever a pre-determined pressure is exceeded in the chamber 20.

Operating pressure fluid flows from chamber 20 through a conduit 30 and throttle 32 to a 40 port 34 of a reversing valve chamber 36. From port 34, operating fluid is directed around land 38 of a reversing valve 40 to a reciprocating motor 42 via port 44 and conduit 46 to a cylinder chamber 48 or via port 50 and conduit 52 to a cylinder chamber 54 of smaller displacement.

The motor 42 is provided with a piston 56 connected by a rod 58 to a table 60 by means of link 62.

Reversing valve 40 is hydraulically shifted and controlled by pilot valve 64. Dogs 66 and 68 attached to the table 60 are positioned to contact and shift arms 70 and 72, respectively, at the extreme right or left travel of the table 60. Arms 70 and 72 are fastened to shaft 74 which in turn carries a ball joint arm 76 for shifting pilot valve 64. Therefore, as illustrated, when the table 60 has reached its extreme travel to the right, dog 66 will contact arm 70 and shift pilot valve 64 to the left.

When the pilot valve 64 has been shifted to the left as illustrated in the drawing, pressure fluid is admitted to the righthand end of reversing valve 40 for shifting it to the left. The hydraulic fluid is communicated from chamber 20 to chamber 78 via conduit 80, ports 82 and 84, conduit 86, and check valve 88. Hydraulic pressure exerted against the right end of valve 40 will shift the valve against the pocketed pressure which is adapted to be metered out of the opposite end thereby controlling the rate of shifting valve 40.

The hydraulic fluid pocketed in chamber 90 is metered out or released as the reversing valve 40 is shifted to the left, by means of the conduit 92, needle valve 94, conduit 96, ports 98 and 100, and conduits 102, 104, and 106, to tank 16. Adjustable positive stops 108 and 110 are provided for limiting the travel of reversing valve 40.

When the table 60 and piston 56 reach their extreme left position, dog 68 will actuate arm 72, thereby shifting pilot valve 64 to the right. Shifting of valve 64 to the right will direct pressure fluid from conduit 80 to chamber 90 at the left end of the reversing valve 40 via ports 112 and 98, conduit 96 and check valve 114. Pressure fluid pocketed in chamber 78 at the right end of the reversing valve 40 will be metered out through needle valve 116, conduit 86, ports 84 and 118, conduits 102, 104, and 106 to tank 16.

During the travel of piston 56 to the left with the valve positioned as shown in the drawing, chamber 48 will be exhausted through conduit 46, ports 44, and 120, conduit 122, port 124, chamber 126, conduits 26 and 28 to tank 16. In the reverse direction, chamber 54 exhausts through conduit 52, ports 50 and 128, conduit 130, port 132, exhaust chamber 126, exhaust conduits 26 and 28 to tank 16.

The speed of table 60 is controlled by the pressure fluid flow rate through conduit 30 which in turn is controlled by the combination throttle 32 and compensating valve 22. The valve 22 is pressure operated by the piston 134 in conjunction with the spring 136. The difference in pressure between chambers 20 and 138 on either side of the piston 134, in cooperation with spring 136, will control the opening and closing of valve 22. It will be noted that chamber 20 and the upper side of piston 134 are subject to the operating pressure ahead of the throttle 32, while chamber 138 and lower side of piston 134 are subject to the operating pressure beyond the throttle 32 and communicated thereto by conduit 140. A restriction 142 and pilot relief valve 144 are provided in conduit 140. A relief valve chamber 146 is connected to tank 16 by conduits 148, 150, and 106.

At the lower end of compensating valve 22 an auxiliary piston 152 is provided in a cylinder 154 which is connected by a conduit 156 and port

44 to the operating conduit 46 of the larger motor cylinder chamber 48. A drain 158 for cylinder 154 above the piston 152 is provided in an auxiliary piston rod or stem 160. The drain 158 connects to an axial drain 162 in the compensating valve 22 which in turn leads to tank conduits 26 and 28.

In operation, pressure-operating fluid is directed to chamber 54 of motor 42 from tank 16 via conduit 14, pump 10, conduit 18, chamber 20, conduit 30, throttle 32, ports 34 and 50, and conduit 52. The rate of travel of piston 56 and table 60 will depend upon the hydraulic flow rate or pressure drop through throttle 32.

The flow control device, comprising the compensating valve 22, throttle 32, conduit 140 and relief valve 144, provide a means for controlling the travel rate of the motor piston 56. The compensating valve piston 134 is of the double-acting, pressure-balanced type wherein the upper face is subjected to the operating fluid pressure in chamber 20. The pressure in chamber 138 is communicated from a point beyond the throttle 32 through conduit 140. The compensating valve 22 shown in the drawing is of the relief type wherein excess pressure ahead of the throttle 32 is relieved through conduits 26 and 28 to tank 16.

The spring 136 of pre-determined compressive force urges the valve 22 into a closed position. Assuming equal piston areas, if the difference in fluid pressure between chamber 20 and chamber 138 was equal to the normal force of spring 136, the compensating valve 22 would be balanced in a closed position. If the fluid pressure ahead of the throttle in chamber 20 was greater than the pressure beyond the throttle in chamber 138 by an amount greater than the force of spring 136, the valve 22 would open, thereby reducing the pressure in chamber 20 until the drop in pressure across the throttle became equal to the pre-determined force of the spring 136. Therefore, by maintaining a constant pressure drop across the throttle 32, the hydraulic flow rate in conduit 30 is controlled.

Uniform pressure operation is provided by means of the relief valve 144 which is connected to tank 16 via chamber 146 and conduits 148, 150, and 106. When the fluid pressure beyond the throttle 32 becomes excessive, the relief valve 144 will open to relieve the pressure in chamber 138 and permit the main valve 22 to open. The replenishing flow from conduit 30 to chamber 138 through conduit 140 is restricted at 142, whereby the unobstructed flow from chamber 138 to valve 144 is greater than the replenishing supply from conduit 30 through restriction 142.

As described above, under normal operation of the compensating valve 22 and throttle 32, the constant flow is dependent upon the drop in pressure through the throttle 32 which in turn is dependent upon the pre-determined compressive force of spring 136. To change the pressure drop and flow rate therefor, it is necessary to change the compression of spring 136. Hydraulically-operated piston 152 is adapted to rise in cylinder 154 and further compress spring 136. Consequently, when cylinder chamber 48, the larger of the two motor cylinders, is under operating pressure communicated through port 44 and conduit 46, the piston 152 is also subjected to operating pressure through conduit 156 from port 44. In other words, to maintain equal travel rates of the piston 56 in each direction, the larger chamber 48 would require a greater

flow rate to satisfy the increased displacement. Therefore, the auxiliary piston 152 is connected to a source of operating pressure, such as at port 44, during that portion of the cycle in which an increase in flow rate is necessary.

The feature of modifying the operation of the flow control through a portion of the cycle has been shown for a condition where increased flow rate is desired as, for example, where constant travel of a double-acting differential piston is necessary. The conduit 156 may be connected to any portion of the circuit having a variation in pressure characteristics during the period of required modification merely for the purpose of timing the change in rate. The same effect may be accomplished by setting the control for maximum flow rate and then have the auxiliary piston operate to reduce the tension of spring 136 during the portion of the cycle a reduction in flow rate is desired. Various combinations of control and rate can be accomplished by merely having the auxiliary piston respond to a selected cyclic function or functions.

Although the auxiliary means and preferred method for modifying the flow rate has been illustrated and described as modifying the compensating valve operation, it may be linked to the throttle instead. In the latter case the auxiliary control could be made to vary the throttle directly or control a hydraulic conduit adapted to by-pass the throttle, or other ways of modifying the throttling action.

It will thus be seen that the present invention has provided a control for transmission systems having a normally constant flow rate but, at the same time, includes features for modifying the rate through any selected portion of the cycle of operation. This is accomplished by a pressure-actuated auxiliary piston adapted to modify the normal flow control rate and includes means for limiting the communication of actuating pressure to that portion of the operating cycle during which the desired modification is required.

While the form of embodiment of the invention as herein disclosed constitutes a preferred form, it is to be understood that other forms might be adopted, all coming within the scope of the claims which follow.

What is claimed is as follows:

1. A flow control valve for a hydraulic power transmission employing a pressure fluid source and a reversible fluid motor of the reciprocating differential piston type, comprising a throttle and pressure actuated compensating valve controlled by fluid pressure ahead of and beyond the throttle for maintaining a constant fluid flow rate to the end of the motor having the smaller displacement, and auxiliary hydraulic means actuated by operating fluid pressure supplied to the end of the motor having the larger displacement for modifying the normal compensating valve operation and increasing the fluid flow rate to the larger displacement end of the motor during that portion of the motor cycle when the larger displacement end of the motor is supplied with pressure fluid.

2. A flow control valve for a hydraulic power transmission employing a pressure fluid source and a reversible fluid motor of the reciprocating differential piston type, comprising a throttle and pressure actuated compensating valve controlled by fluid pressure ahead of and beyond the throttle for maintaining a constant fluid flow rate to the end of the motor having the smaller

displacement, and an auxiliary piston and a resilient link positioned between the compensating valve and the auxiliary piston for modifying the compensating valve operation when the

5 auxiliary piston is actuated by pressure fluid supplied to the larger displacement end of the motor for increasing the fluid flow rate to the end of the motor having the larger displacement.

3. A flow control device for a hydraulic trans-

10 mission including a throttle in combination with a pressure actuated compensating valve for maintaining a constant pressure drop across the throttle, and auxiliary pressure actuated means for modifying the action of the compensating valve during a part of the cycle and changing the flow rate through the throttle, said auxiliary means being actuated by fluid pressure from that portion of the circuit in which the flow rate is to be changed during that part of the cycle.

15 20 4. A flow control device for a hydraulic transmission including a throttle in combination with a pressure actuated compensating valve, including a piston exposed to pressure ahead of and beyond said throttle for maintaining a constant pressure drop across the throttle, and pressure actuated means for modifying the operation of the compensating valve including an auxiliary piston linked to the compensating valve, and auxiliary pressure fluid conduits connecting the auxiliary piston to a pressure fluid operated element of the transmission requiring a modified flow of pressure fluid during a part of the work cycle.

25 30 5. A flow control device comprising a throttle in combination with a pressure balanced piston type compensating valve, one side of the valve piston being subject to fluid pressure beyond the throttle for increasing the flow rate, the other side of the balanced piston being subject to fluid pressure ahead of the throttle, and tending to decrease the flow rate, a spring providing a pre-determined compression force adapted to assist the pressure fluid from beyond the throttle thereby tending to upset the pressure balance

35 40 45 50 and produce a pre-determined pressure drop across the throttle in proportion to the spring compression, and auxiliary pressure means for automatically changing the spring compression and modifying the pressure drop across the throttle thereby varying the hydraulic fluid flow rate through the control.

6. A flow control device for a hydraulic trans-

55 mission comprising a throttle in combination with a pressure balanced piston type compensating valve, one side of the valve piston being subject to fluid pressure beyond the throttle for increasing the flow rate, the other side of the balanced piston being subject to fluid pressure ahead of the throttle, and tending to decrease the flow

60 65 70 rate, a spring providing a pre-determined compression force adapted to assist the pressure fluid from beyond the throttle thereby tending to upset the pressure balance and produce a pre-de-

75 75 80 85 90 95 100 termined pressure drop across the throttle in proportion to the spring compression, an auxiliary piston adapted to change the spring compression and modify the pressure drop across the throttle during a certain portion of the cycle, the auxiliary piston being connected to and actuated by fluid pressure from a part of the transmission circuit subjected to operating pressure during that cer-

tain portion of the cycle.

7. A hydraulic transmission comprising a source of operating pressure fluid, a hydraulic motor of the reciprocating double acting differential piston type,

a flow control device including a throttle in combination with a pressure actuated compensating valve controlled by fluid pressure ahead of and beyond the throttle for maintaining a constant pressure drop and fluid flow rate through the throttle when normally supplying operating pressure fluid to the motor, and an auxiliary hydraulic means linked to the compensating valve for modifying the flow rate in proportion to the displacement of the motor cylinder being filled thereby maintaining an equal rate of travel of the motor piston in both directions regardless of displacement.

8. A hydraulic transmission comprising a source of operating pressure fluid, a hydraulic motor of the reciprocating double acting differential piston type, a flow control device including a throttle in combination with a pressure actuated compensating valve controlled by fluid pressure ahead of and beyond the throttle for maintaining a constant pressure drop and fluid flow rate through the throttle when normally supplying operating pressure fluid to the motor, and means for equalizing the rate of travel of the hydraulic motor piston in both directions including a hydraulically operated piston for automatically modifying the operation of the compensating valve during a part of the motor operating cycle.

9. A hydraulic transmission comprising a source of operating pressure fluid, a hydraulic motor of the reciprocating double acting differential piston type, a flow control device including a throttle in combination with a pressure actuated compensating valve controlled by fluid pressure ahead of and beyond the throttle for maintaining a constant pressure drop and fluid flow rate through the throttle when normally supplying operating pressure fluid to the motor, and an auxiliary hydraulic means linked to the compensating valve for modifying the flow rate in proportion to the displacement of the motor cylinder being filled thereby maintaining an equal rate of travel of the motor piston in both directions regardless of displacement, the auxiliary means being actuated and controlled by operating pressure during that portion of the cycle in which the flow rate is modified.

10. A hydraulic transmission comprising a source of operating pressure fluid, a hydraulic motor of the reciprocating double acting differential piston type, a flow control device including a throttle in combination with a pressure actuated compensating valve controlled by fluid pressure ahead of and beyond the throttle for maintaining a constant pressure drop and fluid flow rate through the throttle when normally supplying operating pressure fluid to the motor, and means for equalizing the rate of travel of the hydraulic motor piston in both directions including a hydraulically operated piston for automatically modifying the operation of the compensating valve during a part of the motor operating cycle, and hydraulic conduits connecting the piston to a part of the transmission circuit carrying operating pressure during the modified portion of the motor cycle.

11. A flow control device for a hydraulic transmission including a throttle in combination with a pressure actuated compensating valve for maintaining a constant pressure drop across the throttle, and auxiliary pressure actuated means for modifying the action of the flow control device during a part of the cycle and changing the flow rate through the throttle, said auxiliary means

being actuated by fluid pressure from that portion of the circuit in which the flow rate is to be changed during that part of the cycle.

12. A flow control device comprising a throttle in combination with a pressure balanced piston type compensating valve, one side of the valve piston being subject to fluid pressure beyond the throttle for increasing the flow rate, the other side of the balanced piston being subject to fluid pressure ahead of the throttle, and tending to decrease the flow rate, a spring providing a pre-determined compression force adapted to assist the pressure fluid from beyond the throttle thereby tending to upset the pressure balance and produce a pre-determined pressure drop across the throttle in proportion to the spring compression, and auxiliary pressure means for automatically modifying the operation of the flow control device during a portion of the cycle requiring an abnormal demand.

13. A flow control device for a hydraulic transmission having a pressure fluid source and a pressure fluid operated element requiring a regulated modified flow rate and comprising in combination a first throttle valve and a second throttle valve in series, the first of which includes first operating means responsive to the pressures ahead of and beyond the second throttle for maintaining a constant pressure drop across the second throttle, a second pressure responsive operating means operatively connected to one of said throttles for modifying the pressure drop across the second throttle, and at least one hydraulic conduit adapted to be connected to the fluid operated element requiring the modified flow rate and connected to the second operating means for supplying pressure fluid thereto for operating the same and thereby modifying the flow rate in said conduit leading to the fluid operated element.

14. A flow control device for a hydraulic transmission having a pressure fluid source and a pressure fluid operated element requiring a regulated modified flow rate and comprising in combination a throttle and a pressure compensating valve in series, the compensating valve including operating means responsive to the pressures ahead of and beyond the throttle for maintaining a constant pressure drop across the throttle, a second pressure responsive operating means connected to the compensating valve for causing the latter to modify the pressure drop across the throttle, and at least one hydraulic conduit adapted to be connected to the fluid operated element requiring the modified flow rate and connected to the second operating means for supplying pressure fluid thereto and causing the compensating valve to modify the pressure drop across the throttle and thereby modify the flow rate in said conduit leading to the fluid operated element.

15. A flow control device for a hydraulic transmission having a pressure fluid source and a pressure fluid operated element requiring a regulated modified flow rate and comprising in combination a throttle and a pressure compensating valve in series, the compensating valve including operating means responsive to the pressures ahead of and beyond the throttle for maintaining a constant pressure drop across the throttle, a second pressure responsive operating means connected to the compensating valve for causing the latter to modify the pressure drop across the throttle, and at least one hydraulic conduit for supplying pressure fluid to the second operating

means and adapted to be connected to the pressure fluid source during that portion of the transmission cycle in which the pressure fluid operated element requires a modified flow rate.
